UNITED STATES PATENT OFFICE.

WILLIAM E. CLAY, OF NANTASKET BEACH, MASSACHUSETTS.

LABEL OR STAMP AFFIXING DEVICE.

1,273,331.

Specification of Letters Patent. Patented July 23, 1918.

Application filed May 17, 1916. Serial No. 98,204.

To all whom it may concern:

Be it known that I, WILLIAM E. CLAY, a citizen of the United States, residing at Nantasket Beach, in the county of Plymouth 5 and State of Massachusetts, have invented new and useful Improvements in Label or Stamp Affixing Devices, of which the following is a specification.

This invention relates to devices for affixing labels, stamps or the like to articles.

The object of the invention is to provide a simple and inexpensive device of the nature set forth which is particularly adapted for both office or individual use and eliminates the necessity of employing the slow methods now employed in offices, consisting of the moistening of the gummed substance on the stamp by rubbing the same over a dampened sponge or the very unsanitary 20 method of moistening a portion of the envelop or the gummed surface of the stamp by applying to the tongue.

In its present adaption the device as shown is adapted to be manually operated, while 25 the material or work to which the label or stamp is to be attached is, in the present embodiment, manually placed in its proper position. It is needless to state, however, that a power driven device or instrumentalities for feeding the work may be employed 30 without departing in the least from the spirit or scope of the invention.

In accordance with one feature of my invention the movement of the pad toward 35 the work to press the stamp or label thereagainst is utilized to operate means for advancing the strip into a position to be engaged by said pad. Another feature of the invention consists in providing means for 40 moistening the surface of the work during the insertion of the work so that when the strip is moved into contact with the work it will adhere thereto. The accomplishments of the objects hereinbefore set forth 45 are attained by the mechanism illustrated in the accompanying drawings in which:

Figure 1 is a side elevation of a device embodying my invention.

Fig. 2 is a sectional plan view taken on 50 the line 2—2 of Fig. 1.

Fig. 3 is a section taken on the line 3—3 of Fig. 2, the plunger and grippers being illustrated in the positions which they occupy when the stamp is being affixed to the envelop.

Fig. 4 is a section taken substantially on the line 4—4 of Fig. 2, illustrating the adjustable gage for positioning the envelop on the work support.

Fig. 5 is a detail sectional view of the 60 grippers and immediate portions of the strip holding means, cutters and gripper holding and releasing means, the section being taken substantially on the line 3—3 of Fig. 2.

Fig. 6 is a section taken on the line 6—6 65 of Fig. 2, illustrating the cutters, pad and moistening instrumentalities in the positions which they occupy when the work is being inserted in the device.

Fig. 7 is a section similar to Fig. 6, illustrating the pad in a lowered position, the moistening pad lifted from the work and the cutters just about being operated to sever the strip.

Fig. 8 is a detailed sectional view of the 75 cutters in their closed positions.

Like numerals refer to like parts throughout the several views of the drawings.

In the drawings, 10 is a work support against which the work to which the stamp 80 or label is to be attached is placed and held during the affixing of said label or stamp. A gage 11 on said work support serves as a stop against which one end of the work is placed so as to position the same in one 85 direction. Coöoperating with said gage 11 is an adjustable gage 12 which is adapted to be moved longitudinally of the gage 11, the construction and arrangement of said gage being illustrated in Fig. 4. The labels or 90 stamps to be affixed to the work may be fed either by short strips or from a roll, preferably the latter, as shown at 13, which form is illustrated in the present adaptation of my invention. 95

The roll 13 is preferably mounted upon an arbor 14 between brackets 15 and 16 mounted upon the frame of the device preferably embodying the work support 10. The brackets 15 and 16 are provided with slots 17 100 adapted to receive the ends of the arbor 14, thus positioning said arbor and the roll carried thereby. The end 18 of the strip is led beneath a guide roll 19 pivotally mounted between the brackets 15 and 16 and thence 105 beneath a pivoted member 20, the forward end 21 thereof being yieldingly pressed toward a plate 22 by means of a spring 23, preferably coiled about a rod 24 which extends from the bracket 15 to the bracket 16 110

through ears 25 formed upon the pivoted member 20.

The member 20 and the plate 22 constitute a holder for the end of said strip while the edges of said strip are guided preferably between the brackets 15 and 16, the same being continued from the roll 13 substantially to the edge of the gage 11. The surface of the plate 22 which is engaged by the strip 10 is arranged at a distance from the surface of the work support 10 and terminates at a slight distance back of the edge constituting the gage 11, whereby the end 18 of the strip will be permitted to project forwardly beyond the holder therefor.

Means are provided for advancing the forward end of the strip of sheet material over the portion of the work which is supported on the work support against the gage 11. A 20 simple and efficient means for accomplishing this result consists of a pair of grippers 26 and 27 constructed and arranged to be moved toward and away from the holding means embodying the pivoted member 20 and plate 22. The gripper 26 is preferably arranged to slide in suitable guides 28, 28 preferably formed upon a plate 29 superimposed above the work support 10 and between said plate and said work support is a 25 recess 30 of a sufficient depth to receive the work. The gripper 27 is pivotally attached to the gripper 26 by a pin 31, extending through ears 32 and 33 formed respectively upon the grippers 26 and 27.

35 The strip engaging ends 34 of the grippers 26 and 27 are normally held closed by a spring 35 preferably encircling the pin 31 and with its ends engaging the inner faces of the grippers 26 and 27 respectively. The 40 grippers are at the proper time moved away from the strip holding members consisting of the member 20 and the plate 22 to feed or advance a portion of the strip over the work upon the work support 10, said work being illustrated at 36, and after having 45 been advanced the desired distance the grippers are caused to release the strip after which the advanced end is moved into contact with the work 36.

50 The instrumentalities for moving the advanced portion of the strip toward said work support and against said work to affix said strip thereto preferably includes a pad 37 having a substantially resilient work engaging portion 38. The pad 37 is attached to a plunger 39 mounted in suitable guides to reciprocate laterally or toward and away from the face of said work support against which the work 36 rests.

55 Mounted upon said plunger and normally movable therewith is a slide 40, said slide being arranged to reciprocate in suitable guides, in the present instance consisting of rods 41, 41 projecting upwardly from the

plate 29. The outer ends of the rod 41 are 65 tied together by a plate 42. The plunger 39, although having slidable engagement with the slide 40, is normally prevented from moving relatively to said slide by a spring 43 which engages a portion of said slide and 70 a pin 44 on said plunger.

By reason of this construction, when the plunger 39 is moved toward the work support 10 the slide 40 will likewise be moved toward said work support until resistance 75 is encountered, whereupon a further movement of the slide will be prevented but the plunger and pad will continue until the resilient face of said pad engages the work. When pressure is removed from the plunger 80 the spring 43 causes said plunger to return to its normal position relatively to the slide. The slide 40 is preferably provided with a tubular extension 45 which has sliding engagement with the plate 42 and also with the 85 rod or plunger 39.

The tubular extension 45 is provided at its outer end with a collar 46 engaging one end of a spring 47 encircling said tubular extension while the opposite end of said spring 90 engages said plate. The function of this spring is to return the slide and plunger to their normal positions when pressure is removed from the end of said plunger. A hand piece 48 is attached to the outer end of the plunger, whereby the same may be more easily pushed and as previously stated the action of the plunger 39 toward the work support is utilized to move the grippers to advance the strip over the work.

100 A very simple and efficient method of accomplishing such a coöperation consists in providing a bell crank lever 49, the same being pivoted at 50 to a fixed portion of the device. One arm of the lever 49 is pivotally attached to the slide 40 by means of a pin 51 working in a slot 52 in one end of said lever and as the slide 40 is reciprocated the lever 49 will be rocked upon its pivot 50. The other arm 53 of the lever 49 is operatively connected with the slidably arranged gripper 26 by means of a pin 54 mounted preferably in ears 55 carried by said gripper 26. The pin 54 is arranged within a slot 56 adjacent to the outer end of the arm 115 53 whereby the reciprocatory movements of the slide 40 will be imparted to the sliding gripper 26.

110 Not only are the reciprocatory movements of the plunger 39 and slide 40 utilized to move the grippers to advance the work, but the same means are utilized to move said grippers toward the strip holding means to secure a fresh strip, this taking place after the strip which was advanced by the movement of the pad toward the work has been pressed against said work. Furthermore, the same movements of said plunger are also

preferably employed to accomplish the operation of said grippers to grip and release the strip thus advanced.

To facilitate these operations the arm 53 of the lever 49 is extended at 57 so as to engage the arm 58 of the pivoted gripper 27, said arm 58 being upon the opposite side of the pivot 31 from the work engaging ends of said grippers. The extension 57 is so arranged that it engages the arm 58 at a certain time during the movement of the grippers away from the holders 21 and 22, whereby the pivoted member 27 will be rocked upon said pivot 31 and the jaws 15 opened.

Coöperating with the pivoted gripper 27 is a latch 59, said latch being preferably pivotally mounted upon the slideable member 26 of the pair of grippers and adapted 20 to automatically engage the free end of the arm 58 when said arm is depressed by the extension 57 to open the jaws and thus retain said jaws open. An extension 60 on said latch 59 is of sufficient weight to cause 25 said latch to engage said arm 58 when said arm has been depressed, as illustrated in Fig. 3.

The work engaging ends 34 of the grippers are preferably held open by the latch 30 59 until said grippers have been returned to their positions adjacent to the holding means for the end of the strip of material to be advanced, with the protruding end of said strip projecting between the gripping 35 ends of said grippers. The closing of the jaws of said grippers is preferably accomplished by withdrawing the latch from the end of the arm 58 and during the initial movement of the plunger 39 and slide 40 to 40 toward the work support.

A simple device for accomplishing this result preferably includes a spring pin 61 mounted in the arm 53 of the lever 49, said pin being adapted to be moved into contact 45 with the latch 59 and to rest within a slight depression 62 during the return of said grippers to their normal positions as indicated in Fig. 1, or, in other words, during the outer movement of the pad 37 with respect to the 50 work support. This particular construction, however, is but one of a large number of simple expedients capable of accomplishing the same result, one of such being a pivoted latch which can be attached to the arm 53 55 so as to swing about its pivot when the arm 53 moves in the direction of the arrow *a*, but when the arm moves in the opposite direction it will cause said latch to be disengaged from the arm 58.

60 When exceptionally thin strips of paper are employed and one of the surfaces thereof is gummed, there is great tendency of said material to curl up at the ends and to prevent this from taking place and thus in-

terfering with the grippers taking hold of 65 said end the end 21, pivoted member 20 and the plate 22 are provided with teeth 63 which coöperate or interlock with teeth 64 formed at the work engaging ends 34 of said grippers, thus when said grippers are 70 moved toward the holder the ends of said grippers will overlap the ends of said holders.

When the strip is continuous it is necessary that the advanced portion thereof be 75 severed before the pad 37 engages the same and for this purpose are preferably provided cutters 65 arranged in close proximity to the ends of the holders 21 and 22. The cutters 80 preferably embody a stationary blade 66 and a movable blade 67 pivoted at 68 to said blade 66. A spring 69 is attached at 70 to the blade 67 and at 71 to a fixed portion of the device so as to exert a yielding pressure upon the blade 67 to retain the same in its 85 uppermost position. The space between the blades 66 and 67 is normally sufficient to admit the strip engaging ends 34 of the grippers to engage the end of said strip.

The cutter 67 is preferably operated by a 90 cam plate 72 attached to the slide 40 and adapted to be moved by the same into contact with said cutter during the latter portion of the movement of said slide toward the work support and after the cutters 67 95 have been moved sufficient to sever the end of the strip a further movement of said slide is prevented by reason of said slide engaging a portion of the cutter 66 at 73, said portion constituting a stop for said slide, said stop 100 constituting the resistance hereinbefore referred to for said slide which causes the plunger 39 to be moved relatively to said slide for a short distance or sufficient to cause said pad 37 to engage the work at 105 which time the spring 43 is compressed.

It is not essential, although preferable, that the under face of the strip be gummed as stamps and labels usually are and when so used it is necessary that moisture be provided to moisten said gummed surface so that the stamp or label will adhere to the work when pressed against said work by the pad 37. A simple and efficient means for accomplishing the moistening of said 110 gummed substance preferably consists of a moistening pad 74. This pad includes a holder 75 containing a liquid absorbing substance 76. The lower portion of the holder 75 is perforated at 77 and these perforations 115 are preferably covered with a porous material 78, such as felt, said felt being normally held against the face of the work support 10.

The holder 75 is mounted upon an arm 79 and is preferably pivoted at 80 to the stationary portion of the device. A spring 81 engages said arm and yieldingly retains the felt portion 78 of said pad in contact with 120 125

the work support. Moisture is supplied to the absorbent material 76 preferably through a flexible tube 82 which extends to a reservoir 83 containing a supply of liquid. A wick 84 may be inserted in the tube 82 whereby the moisture may be fed gradually from the reservoir to the absorbent 76, thus insuring a constant supply of liquid at the end of said moistening pad. The portion 10 of said moistening pad which engages the work support is preferably rounded as shown in the drawings to enable the work 36 to be easily inserted in the direction of the arrow *b*, Fig. 7, and as said work is 15 inserted the pressure of the spring 81 on said pad causes more or less moisture to be placed upon the upper surface of the portion of said work which is engaged by said pad, leaving said surface moist so that when the 20 severed portion of the strip as indicated at 85, Fig. 7, is moved toward the work by the pad 37 the adhesive substance at the bottom of said strip will be moistened sufficient to cause the strip to adhere. It is desirable that 25 the pad 74 be slightly raised from the work after the same has been inserted to its full extent and to accomplish this result an arm 86 extends upwardly from the arm 79 and is bent at 87 to form a cam surface which 30 co-operates with a roll 88 carried by the slide 40 to elevate said pad as will be readily seen by referring to Figs. 6 and 7 of the drawings.

When it is desired to insert the work farther than it is shown in Fig. 7 the gage 12 must be moved as stated. This is particularly desirable when two or more stamps are to be placed upon an envelop or package. To accomplish this adjustment of the gage 40 12 a lever 89 is pivotally attached to a portion of the gage 12 beneath the work as at 90 while the end 91 of said lever 89 is adapted to project upwardly into engagement with recesses 92 formed in said work support at 45 suitable distances apart according to the spacing of the stamps desired.

A spring 93 normally retains the end 91 within one of the recesses 92. A finger piece 94 is provided on said lever 89, whereby said 50 lever may be readily rocked as desired and the gage 12 moved thereby to a different recess and thus vary the distance to which the

work may be inserted beneath the stamp affixing instrumentalities.

During the movement of the pad 37 toward the work support it has to pass through an opening or hole 95 in the plate 29 when such a plate is employed. This hole is made slightly larger than the stamp or label which is to be affixed to the work and in order that 60 said stamp may be properly guided after it has been severed and further prevented from twisting or turning a guide member 96 is secured to said plate 29 upon the opposite side of the hole 95 of the gage 11. 65

Co-operating with said gage 11 to properly guide said stamp the rounded nose of the moistening pad 74 is also placed so as to form a guide for that side of the stamp or label which is being affixed and upon the 70 opposite side of the hole from said moistening pad 74 is another plate or guide 97 thus all four sides of the stamp will be guided during the movement thereof toward the work support after it has been severed by 75 the cutters 65.

Having thus described my invention what I claim and desire by Letters Patent to secure is:

A device of the class described having, in 80 combination, a work support, an affixing pad movable toward and away from said work support, means for positioning predetermined portions of the work in alinement with said affixing pad, means for feeding a 85 strip of sheet material into a position between said affixing pad and the work, a moistening pad movable toward and away from said work support, and means operatively connecting said moistening pad with 90 said affixing pad adapted to permit said moistening pad to engage said work support only when said affixing pad is in its uppermost position away from said work support, whereby the work may be moistened during the insertion thereof. 95

In testimony whereof I have hereunto set my hand in presence of two subscribing witnesses.

WILLIAM E. CLAY.
